ELECTRIC LAMP BASE

David Borowitz, Chicago, Ill.

Application January 19, 1955, Serial No. 34,063

Term of patent 3½ years

(Cl. D48—20)

Fig. 1 is a front elevational view of an electric lamp base showing my new design; and

Fig. 2 is a top plan view thereof.

The broken lines in Fig. 1 indicate the lamp socket.

The dominant features of my new design lie in the portions shown in full lines.

I claim:

The ornamental design for an electric lamp base, substantially as shown and described.
